(57) **CLAIM**

The ornamental design for a brake/ballast assembly, as shown and described.

DESCRIPTION

FIG. 1 is a top-front-left side perspective view of a brake/ballast assembly;

FIG. 2 is a front elevation view of the brake/ballast assembly;

FIG. 3 is a back elevation view of the brake/ballast assembly;

FIG. 4 is a left side elevation view of the brake/ballast assembly;

FIG. 5 is a right side elevation view of the brake/ballast assembly;

FIG. 6 is a top plan view of the brake/ballast assembly; and, FIG. 7 is a bottom plan view of the brake/ballast assembly. The broken lines showing portions of the brake/ballast assembly forms no part of the claimed design.

1 Claim, 4 Drawing Sheets
